UNITED STATES PATENT OFFICE.

WILLIAM S. HAMM, OF CHICAGO, ILLINOIS, ASSIGNOR TO THE ADAMS & WESTLAKE COMPANY, OF ILLINOIS.

DESIGN FOR A WASHSTAND.

SPECIFICATION forming part of Design No. 32,046, dated December 26, 1899.

Application filed November 18, 1899. Serial No. 737,524. Term of patent 14 years.

To all whom it may concern:

Be it known that I, WILLIAM S. HAMM, a citizen of the United States, residing at Chicago, county of Cook, and State of Illinois, have invented and produced a new and original Design for Washstands, of which the following is a specification, reference being had to the accompanying drawings, forming a part thereof, in which—

10 Figure 1 is a plan view of the washstand. Fig. 2 is a front elevation of the same, and Fig. 3 is a transverse section.

15 The slab or table A of the washstand is approximately square in general outline, its front corners, however, being rounded and its upper face is centrally depressed to form the usual bowl. Along one edge of the slab or table there rises a vertical splash-rail B, which is oblong rectangular in contour, and 20 from the front surface of this rail there projects a bracket or console C. The bracket or console may be roughly described as having the form of the quadrant of a flattened sphere,

one of the radial faces being coincident with the surface of the splash-rail and the other 25 constituting the upper surface of the bracket or console. The curvature of the outer face of the bracket or console deviates from the curvature of the sphere in that the curvature of its vertical median line is straightened as 30 it approaches the surface of the splash-rail. The upper surface of the bracket or console C is centrally depressed, as shown.

The essential feature of the design is the bracket or console C springing from the front 35 face of the splash-rail, and is shown in solid lines, the remaining and less important features of the design being shown in dotted lines.

I claim as my invention—

The design for a washstand, as herein shown 40 and described.

WILLIAM S. HAMM.
